UNITED STATES PATENT OFFICE

CHARLES A. DREISBACH, OF NEW HAVEN, CONNECTICUT

SAND-BLAST DEVICE

Application filed April 6, 1927. Serial No. 181,402.

My invention relates to a sand blast device for cleaning long strips, wires or rods, and the same is adapted to accomplish the same purpose as the device shown in the patent to 5 Washburn No. 1,400,585. In the present device a strip, bar, or rod of material, usually metal, which is to be cleaned by a sandblast, is passed in a long or continuous length through the sand blast portion of the device 10 so that a blast of sand and air at high velocity is projected against the surface of the member which is being cleaned, and during the operation the wire, rod or other member under treatment passes continuously through 15 the sand blast nozzle in order that the treatment may be carried out as a continuous operation on a very long strip of material. One object of the present invention is to improve the construction and assembly of the sand 20 blast nozzle and its associated parts in order that the parts may be made in the simplest and most economical manner and in order that the parts may be assembled and disassembled quickly. Another advantage is that 25 the parts of the sand blast nozzle which are subject to rapid wear may be removed and replaced quickly and at a very low cost. Another advantage is that the portion of the nozzle which determines the shape and 30 position of the blast of sand may be shaped in various ways to suit the particular cross section of the material under treatment. Other advantages will appear in the following detailed description of my invention.

35 In the drawing forming part of this application,

Figure 1 is a longitudinal, sectional view through the center of a sand blast device embodying my invention,

40 Figure 2 is an end elevation thereof taken from the left hand end of Figure 1,

Figure 3 is an elevation of the discharge nozzle detached from the casing, and

Figure 4 is a sectional view taken on the 45 line 4—4 of Figure 1.

The present device includes a frame or casing made principally in two assembled sections. One of these sections shown at 1 has a rear wall 2 provided with a rear socket 50 or opening 3 to receive a compressible or

soft packing 4 through which a strip of material 5 under treatment is adapted to pass, this packing serving to prevent back flow of the air and sand. There is a central hub 6 projecting inwardly from the end wall 2 and this has a central bore 7 somewhat larger in diameter than the largest strip of material to be treated in the device. In addition, the shell member 1 has a tubular projection 8 to which the air hose 9 is adapted to be connected for directing the current of compressed air into the chamber 10 formed within the casing member 1. It is understood that the pipe or tube 9 is connected with a suitable reservoir of an air compressing machine of any well known construction, the air compressor being omitted from the drawings as it forms no part of the present invention and such devices are well known in the art. The casing member 1 also includes 15 a top wall 11, a bottom wall 12 and end walls 2, 13 all serving to define the air chamber 10 which surrounds the tubular extension 6 through which the strip of material passes. In the present construction the members 20 which form the sand blast nozzle or which control the form and direction of the blast are adapted to be assembled with the casing member 1 and then this member with such parts assembled may be assembled in connection with a second casing member 14 which forms the sand chamber and which carries the discharge nozzle.

The bore of the tubular extension 6 is threaded as shown at 22, to receive a correspondingly threaded shank or extension 51 formed on the rear end of the interior nozzle member 17 the details of which are shown in Figure 3. The remainder of this member 17 is provided with a polygonal outer surface which in the particular form illustrated in the drawing is substantially rectangular, having four faces 18 with the corners removed on the arc of a circle, as shown at 19 in Figure 4, to conform with interior diameter of the second or outer nozzle member. The forward or discharge portion of this nozzle member 17 as shown at 20 is preferably frustro conical in shape, tapering from the ends of the flat faces 18. This nozzle member

also has a bore 21 extending longitudinally through it, of slightly larger diameter than the largest strip of material which is to be subjected to the sand blast action. The nozzle member 17 as above stated, is threaded into the tubular extension 6 and it extends forwardly through the tubular member 8 which is part of the casing member 1; and in the form of the invention shown herein the interior opening or bore of this member 8 is of circular shape to be concentric with the arc of the corners 19 of the nozzle member 17. The outer member of the nozzle proper comprises a circular member 24 having a tubular extension 25 which is provided with an exterior thread which screws into the threaded end 26 of the casing extension 8; and it also has a flange 27 on its exterior which abuts against the forward end of this extension 8 and this joint may be packed with a suitable washer if desired. The nozzle member 24 is provided with a central bore 28 formed on the arc corresponding with the several rounded corners 19 of the inner nozzle member 17 so that the corners of this latter member may fit snugly against the bore 28. The spaces 50 are formed between the flat faces 18 of the member 17 and the bore 28 around the path of the rod 5. From the cylindrical bore 28 of the member 24 the opening decreases or tapers, as shown at 29 toward the discharge end of the nozzle and the diameter along this tapered portion is somewhat larger than the exterior diameter of the frustro conical portion 20 of the inner nozzle member; so that there is formed between these two parts an annular space 30 surrounding the path of the strip of material under treatment.

The other member of the casing comprises the tubular member 14 the rear end of which is closely fitted to the exterior of the tubular extension 8 of the first casing member and it abuts against the shoulder 31 and, if desired, a suitable washer may be interposed at this point to prevent leakage. The casing member 14 is provided with a top opening 32 into which the lower end of a hopper 33 feeds the sand into the sand chamber 34. This casing member forms the compartment 34 which constitutes the sand chamber of the nozzle and it surrounds the discharge end of the nozzle member 24.

The right hand end of this casing member 14 in Figure 1 is provided with a frustro-conical bore 35 extending from the front of the sand chamber to the extreme end of the casing member 14 into which the discharge nozzle 36 is adapted to fit. The discharge nozzle is shown at 36 and it consists of a tubular portion 37 which flares out in frustro conical shape at the left hand end 38 the periphery of this frustro conical portion being adapted to fit snugly into the frustro conical opening of the casing member 14 with the cylindrical portion of the discharge nozzle projecting

beyond the end of the casing member. This discharge nozzle has a frustro conical bore 39 on the left hand end which merges with a cylindrical bore 40 through the center of which the piece of material under treatment 70 is adapted to travel. In order to hold the discharge nozzle tightly in place and to prevent leakage of sand between it and the casing member 14, I have provided a yoke 41 which is adapted to be inserted through the 75 top opening 32 where the hopper is attached to the casing member 14 and this yoke, which is wedge shape, or tapered, is adapted to be forced between the ends of this discharge nozzle 37 and the lugs 42 cast on the interior 80 of the casing member 14 in order to force the discharge nozzle into tight engagement with the frustro conical bore 35 in order that sand will not pass between the discharge nozzle 85 and the casing member 14.

I have not shown the details of the hopper device as any type of hopper may be employed with this device, but preferably the type of hopper shown in the said Washburn Patent No. 1,400,585.

In the operation of the device the strip of material 5 which is to be subjected to the action of the sand blast is passed through the soft packing 4; through the bore of the nozzle member 17, passing through the sand chamber 34 and thence through the discharge nozzle 37; and when the machine is in operation this strip of material may be fed continuously through the apparatus in order that the operation may be carried on as a 100 continuous one. Sand is continually introduced into the sand chamber 34 from the hopper 33 and compressed air is admitted through the pipe 9 into the air chamber 10. The compressed air passes from the air chamber 10 through the bore of the extension 8 and thence through the spaces 50 formed between the polygonal outer surface of the outer nozzle member 24. In the form of the device shown herein a stream of air will be divided into four parts corresponding with the four spaces 50 all disposed concentrically around the axis of the travelling rod of metal 5. From these spaces the compressed air enters the annular space 30 between the frustro conical end 20 of the inner nozzle member and the frustro conical bore 29 of the outer nozzle member, so that the air current is deflected around the entire surface of the rod 5; and as this air passes into the sand chamber, it takes up the sand and projects it at high velocity against the surface of the rod 5. The blast of sand is forced at high velocity through the annular space formed between the travelling rod 5 and the bore of the discharge nozzle 37. This latter nozzle is preferably of considerable length as shown in the drawing, so that as the blast of sand is travelling through this annular space it is frictionally acting upon the entire surface 125 130

of the travelling rod 5 and it serves to remove any scale or corrosion which may be present along the rod, so that the rod emerges from the end of the discharge nozzle in clean condition. The action is more nearly a scouring action as the device does not depend entirely on the impact of the sand against the surface of the rod 5.

It will be apparent that a blast of sand entirely surrounding the travelling rod may

10 be projected against the rod and that the action of the blast may be uniform all around the same, whereas when individual jets or nozzles are employed, as in the Washburn

15 Patent, the velocity of the sand blast is more or less localized at different points on the travelling rod. With the present type of nozzle the jet or blast may be of annular form directed at a constant angle against

20 the periphery of the travelling rod. Furthermore, the nozzle is of very simple and inexpensive construction as the inner and outer members 17, 24 may be easily and inexpensively made. If a rod other than round is to

25 be treated in the device, it is very easy to remove the nozzle members 17, 24 and substitute other nozzle members having the space 30 shaped to conform with the shape of the rod under treatment. For instance, if a rod

30 of oblong cross section is to be treated, then the annular space 30 which controls the deflection of the blast against the rod may be similarly shaped in order that the blast will act uniformly on the surface of the rod.

35 Likewise an oval or any other shaped rod may be uniformly treated by simply supplying the nozzle members in which the annular space 30 is shaped to correspond with the periphery of the particular shaped rod.

40 In assembling the device the inner nozzle member 17 is screwed into the tubular extension 6 of the casing member 1 and then the outer nozzle member 24 is screwed into the tubular portion 8 of the same casing member

45 1; and this will bring the nozzle members into the proper operative relation to form the air passages as herein described. The discharge nozzle is introduced into the bore 30 of the casing member 14 and the wedge yoke 41

50 is then inserted to lock the discharge nozzle in place and after that the two casing members are assembled in the position shown in Figure 1.

Having described my invention, what I

55 claim is:

1. A sanding device adapted to operate upon a long strip of material passing therethrough, comprising a casing forming an air chamber and a sand chamber following said air chamber in the direction of travel of the strip, a tubular member detachably mounted inside said air chamber and projecting into said sand chamber and having a bore through which said strip travels, means for feeding air to said air chamber whereby said air sur-

rounds said tubular member, a second tubular member mounted in said casing to be detachable separately from said first tubular member and disposed in said sand chamber to surround a portion of said first tubular member and co-operating therewith to form an intervening passageway to conduct air from said air chamber into said sand chamber and to project the air and sand against the traveling strip.

2. A sanding device adapted to operate upon a long strip of material passing therethrough, comprising a casing forming an air chamber and a sand chamber following said air chamber in the direction of travel of said strip, said casing having a tubular support in said air chamber and a tubular support opening into said sand chamber,

70 a tubular member detachably mounted in said first tubular support to lie inside said air chamber and to project into said sand chamber, and having a bore through which said strip travels, means for feeding air to said air chamber whereby said air surrounds said tubular member, a second tubular member detachably mounted in said sec-

75 ond tubular support and disposed in said sand chamber to surround a portion of said first tubular member and co-operating therewith to form an intervening passageway to conduct air from said air chamber into said sand chamber and to project the air and sand against the traveling strip.

3. A sanding device adapted to operate upon a long strip of material passing therethrough, comprising a casing forming an air chamber and a sand chamber following said air chamber in the direction of travel of said strip, a tubular member detachably mounted in said air chamber and projecting into said sand chamber and having a bore through which said strip travels, means for feeding air to said air chamber, a second tubular member detachably mounted in said casing

80 and surrounding said first tubular member and co-operating therewith to form an annular space surrounding said strip, said tubular members co-operating to conduct air from said air chamber into said sand chamber and to project the air and sand against the traveling strip.

4. A sanding device adapted to operate upon a long strip of material passing therethrough, comprising a casing forming an air chamber and a sand chamber following said air chamber in the direction of travel of said strip, said casing having a tubular support in said air chamber and a tubular support opening into said sand chamber, a tubular

85 member threaded into said first tubular support to lie in said air chamber and to project into said sand chamber, and having a bore through which said strip travels, means for feeding air into said air chamber, a second tubular member threaded into said second
